UNITED STATES PATENT OFFICE.

JOY S. REYNOLDS, OF SEATTLE, WASHINGTON.

GAS-BURNER.

1,287,437.

Specification of Letters Patent. Patented Dec. 10, 1918.

Application filed November 24, 1917. Serial No. 203,854.

To all whom it may concern:

Be it known that I, Joy S. REYNOLDS, citizen of the United States, residing at Seattle, in the county of King and State of Washington, have invented a certain new and useful Improvement in Gas-Burners, of which the following is a specification.

My invention relates to improvements in gas burners, and the object of my invention is to provide a portable gas burner which shall be so constructed that it shall be adapted to conduct and deliver to a focal point of combustion a plurality of jets of a combustible mixture of gases and a single jet of oxygen, or steam, or air, at which point of combustion said combustible mixture of gases and said oxygen or said steam or said air will be intermingled and there to be ignited to produce a flame of extremely high temperature, and which flame, by a manipulation of the burner, may be directed to impinge upon the surfaces to be heated. A further object of my invention is to provide a burner wherein its tubular body portion is formed of one piece of metal through which is provided a passageway for gas extending from the inlet end to the outlet end thereof whereby there will be no joints formed in said passageway through which gases may leak.

I accomplish these objects by devices illustrated in the accompanying drawings, wherein—

Figure 1 is a view in longitudinal mid-section of the operative parts of a burner embodying my invention;

Fig. 2 is a view of the same in cross-section on broken line 2, 2 of Fig. 1;

Fig. 3 is a view of the same in cross-section on broken line 3, 3 of Fig. 1;

Fig. 4 is a view in longitudinal mid-section of a modified form of burner embodying my invention;

Fig. 5 is a like view of said modified form of burner, which shows a different arrangement of parts thereof;

Fig. 6 is a view in cross-section on broken line 6, 6 of Figs. 4 and 5; and

Fig. 7 is a view in cross-section on broken line 7, 7 of said Fig. 5.

Referring to the drawings, throughout which like reference numerals indicate like parts, as shown in Fig. 1, a tubular body is formed to have a portion 4, preferably of hexagonal cross-section, a portion 5 of smaller diameter whereby is formed an an-

nular shoulder 6 from which projects an annular bead 7, a portion 8 of still smaller diameter, an externally screw-threaded portion 9, a portion 10 of still smaller diameter, and a tapered portion 11 whose inner end portion is surrounded by an integral collar 12.

Extending through the collar 12 in converging lines from the annular surface of its inner side to the annular surface of its outer side, are a plurality of minute apertures 13, the focal point of said converging lines being at a distance from the outer annular surface of said outer side, and the constricted outlet end 14 of the passageway 15 through the tubular body being concentric with the collar 12 whereby a jet of gas emitted from said passageway 15 will be directed in a straight line to said focal point there to mix with the converging jets of a mixture of gases that are emitted from the several apertures 13.

The passageway 15 in the rearward end of the portion 4 is closed by a plug 16.

Extending in a sidewise direction from one side of the portion 4 is an integral externally screw-threaded nipple 17 through which is a passageway 18 that connects with the rearward end portion of the passageway 15.

Connected by a union 19 to the nipple 17 is a conduit pipe 20 that may be extended to a source of oxygen gas or other suitable gas under pressure.

A hexagonal sleeve 21 is disposed to surround the portions 5 and 8 with its rearward end closely fitting the portion 5 and with its rearward annular surface in airtight engagement with the annular bead 7, whereby is provided an annular space 22 between the cylindrical surface of the portion 8 and the inner surface of the sleeve 21.

Another sleeve 23 is disposed to surround the collar 12, the tapered portion 11, the portion 10 and the screw-threaded portion 9, with its rearward annular end surface in airtight engagement with the frontward annular surface of the sleeve 21, said sleeve 23 being provided with a rearward hexagonal portion 24 within which is an inwardly projecting screw-threaded flange 25 whose screw thread operatively engages with the screw thread of the portion 9 thereby to force the rearward end of said sleeve 23 against the adjacent end surface of the sleeve 21.

Extending through said flange 25, from

its annular rearward side to its annular forward side, are a plurality of holes 26 through which gas may flow from the annular space 22 into the annular space 27, between the outer surfaces of the portions 10 and 11 and the inner surface of the sleeve 23, and thence through the minute apertures 13 to the focal point of combustion.

Projecting in a sidewise direction from the sleeve 21, in parallel with the nipple 17 is an integral screw-threaded nipple 28 that is provided with a passageway 29 through it that connects with the annular space 22.

Connected to the nipple 28 by a union 30 is a conduit pipe 31 that may be extended to connect with a source of combustible gas, as acetylene gas or hydrogen gas under pressure.

Suitably supported in a spaced concentric position within the conduit pipe 31 is a smaller pipe 32 which terminates in a constricted nozzle 33 at a point slightly spaced from the entrance to the passageway 29 of the nipple 28, which pipe 32 may be extended to connect with a source of oxygen gas or steam under pressure, whereby said oxygen gas or steam may issue from the nozzle 33 in the form of a jet to mix with the acetylene or hydrogen gas that flows into the passageway 29 from the space between the concentrically disposed pipes 31 and 32.

A burner embodying my invention in the manner hereinbefore described, may be utilized to cut through a plate, a bar, or other mass of metal by melting away portions of such metal along the line of the cut, by connecting the pipes 20 and 32 by flexible hose to a source of oxygen gas under pressure and connecting the pipe 31 by another flexible hose to a source of acetylene or hydrogen gas under pressure, whereupon the oxygen gas from the pipe 32 and the acetylene or hydrogen gas from the pipe 31 will intermingle within the passageway 29 and flow therefrom into the annular space 22 and thence through the holes 26 of the flange 25 into the annular space 27 and thence through the minute apertures 13 to the focal point of combustion, and there be ignited, while the oxygen gas from the pipe 20 will flow through the passageway 18 into the passageway 15 and thence through the constricted outlet end of said passageway 15 directly to said focal point of combustion, thus to accelerate the combustion of the mixture that issues from the apertures 13 whereby to produce a flame of extremely high temperature that will quickly melt steel and other metals.

The flange 25 and the collar 12, being perforated with small holes, serve as a baffle, not only to prevent the flame from striking back into the burner, but they also aid in causing the oxygen and acetylene gases more

thoroughly to mix in the annular spaces 22 and 27.

After the gases have been ignited the pipes 20 and 31 may be grasped by one's hand and manipulated in an obvious manner to dispose the burner to direct its flame against any accessible portion of an object to be melted or heated.

In Figs. 4, 5, 6 and 7, I have illustrated a modified form of my burner which is like the burner shown in Figs. 1, 2 and 3, in mode of operation, but which differs therefrom in the construction and arrangement of certain parts thereof.

In Fig. 4 the parts 34 and 35, which correspond respectively to parts 23 and 21 of Fig. 1, are made to be integral with each other instead of being made in separate pieces, and the part 36, which corresponds to the part 4 of Fig. 1, is provided with a nipple on which is a removable cap 37 in place of a plug 16 of Fig. 1, said cap 37 being interchangeable with a union 38, which corresponds to the union 19 of Fig. 1, and which union 38 is removably connected with a nipple 39 that corresponds to the nipple 17 of Fig. 1.

A nipple 40 corresponds to the nipple 28 of Fig. 1 and in Fig. 4 said nipple 40 is shown as connected directly with the pipe 31 by a union 41 that corresponds to the union 30 of Fig. 1, while in Fig. 5 said nipple 40 is shown as being connected to said pipe 31 by a union 42, a short piece of crooked pipe 43 and a union 44 which corresponds to the union 30 of Fig. 1.

Thus modified, my burner may be changed with respect to the arrangement of its parts so that its flame may be directed, as may be required under different conditions of operation, in a straight line from the pipe 20 as indicated in Fig. 5, or in a line at right angles from said pipe 20 as shown in Fig. 4, the crooked pipe 43 being used only in the former case.

Obviously the body portions 4 and 36 are so formed in one piece to provide passageways for gas that there will be no gases leak from the annular space 27 into the passageway 18 when said gas burner is in operation thereby avoiding any back fire which is a common occurrence in burners heretofore made.

What I claim is:

A gas burner of the class described, which embodies a hollow body portion having two externally screw-threaded nipples on one of its end portions, said nipples having like screw-threads and being disposed with their axes at right angles to each other and each having an inlet passageway that extends therethrough to the interior space of said body portion, the other end portion of said body portion having an integral tubular

portion extending therefrom through which gaseous fluid may flow from said interior space to a point of combustion; a larger tubular portion connected to said other end 5 portion of said body portion and disposed concentrically to surround the integral tubular portion of said body portion to form an annular space therebetween, said larger tubular portion being provided with an externally screw-threaded integral nipple that 10 projects in a sidewise direction therefrom at a point near said body portion and through which nipple extends an inlet passageway that connects with said annular space; an 15 annular collar provided with a plurality of holes extending therethrough from one to the other side thereof and disposed within

said annular space at the outlet end thereof; an internally screw-threaded cap adapted to fit either one of the two nipples of said body portion to close the inlet passageway therethrough; a union adapted to connect a pipe to either one of said two nipples of said body portion, through which pipe gaseous fluid may flow to the space within said body portion; and means connected with the nipple of said larger tubular portion through which gaseous fluid may flow into the passageway thereof. 20 25

In witness whereof, I hereunto subscribe 30 my name this 17th day of November, A. D. 1917.

JOY S. REYNOLDS.
